Primary Examiner — Sheryl Lane*Assistant Examiner* — Mark T. Philippss(74) *Attorney, Agent, or Firm* — Rumit Ranjit Kanakia(57) **CLAIM**

The ornamental design for a hand pump, as shown and described.

DESCRIPTION

FIG. 1 is perspective view thereof of a hand pump showing my new design;

FIG. 2 a front elevational view;

FIG. 3 a rear elevational view thereof;

FIG. 4 a left side view thereof;

FIG. 5 is a right side view thereof;

FIG. 6 is a top plan view thereof; and,

FIG. 7 is a bottom plan view thereof.

The broken lines illustrate portions of the environment structure which forms no part of the claimed design.
